UNITED STATES PATENT OFFICE.

THOMAS ROBERT GILLETT PARKER AND FRED SPENCE, OF ALTRINCHAM, ENGLAND,
ASSIGNORS TO LINOTYPE AND MACHINERY LIMITED, OF LONDON, ENGLAND, A
BRITISH COMPANY.

SHEET-DELIVERY MECHANISM FOR PRINTING MACHINES.

Application filed November 4, 1924, Serial No. 747,738, and in Great Britain November 8, 1923.

This invention relates to sheet delivery mechanism for printing machines, and particularly to mechanism in which a reciprocating carriage for delivering the sheets printed side up, and a fly delivery for delivering the sheets printed side down, may be alternatively operated in conjunction with main delivery tapes by which the sheets are conveyed from the printing cylinders.

10 The reciprocating carriage usually employed in mechanism of this kind, comprises a series of sticks on which the printed sheet rests during the outward stroke of the carriage and from which the sheet is swept on 5 to the delivery board by means of sheet-pushers fingers held against the following edge of the sheet during the inward stroke of the carriage. Apparatus according to the present invention, embodies a known form 15 of reciprocating carriage having a set of endless tapes, the two pulley shafts on which are connected by an endless chain passing over sprockets on the said shafts, chain stop mechanism being provided where- 20 by the chain is held during the inward stroke of the carriage to wind the tapes from beneath the sheet for depositing the latter on the delivery board; and further, ordinary fly delivery mechanism located above the reciprocating carriage so that the fly sticks 25 overlie the latter and act as sheet guards when the printed side up delivery is operating.

Except as hereinafter stated, the mechanism 30 may be of known construction, comprising, for example, a crank-operated rod detachably connected to a lever for reciprocating the carriage, and a cam-operated rack and segment gear for oscillating the fly stick shaft, with means for disconnecting the said gear from the operating cam.

Having in view the object of enabling a reciprocating carriage of the last mentioned form to be operated alternatively with a fly delivery of ordinary form, and enabling the change from either type of delivery to the other to be more expeditiously and conveniently effected than has heretofore been possible, the invention comprises means for 45 adjusting the position of the main tapes relatively to the respective delivery mechanisms, and provides for the ready removal, replacement or adjustment of various parts as hereinafter more particularly indicated.

The invention will now be described by 55 reference to the accompanying drawings in which:

Figure 1 is an elevation of sufficient of a printing machine to illustrate the present improvements, this view being partly broken 60 away and showing the mechanism arranged for delivering the sheets printed side up;

Figure 2 is a view of part of Figure 1 drawn to a larger scale and showing details omitted from the latter figure; 65

Figure 3 is an elevation as seen from the right-hand side of Figure 2, with certain parts omitted, and

Figure 4 is a view similar to Figure 2 but showing the pertinent parts of the mechanism arranged for delivering the sheets 70 printed side down.

The before mentioned delivery carriage is formed of two similar rigidly connected side frames 1, each provided with two wheels 2 adapted to travel along a stationary rail 3, when motion is imparted to said carriage through levers 4 and links 5; all these parts are of ordinary construction, and as the elevations given in Figures 1, 3 and 4 are 80 all of the gear side of the machine, only such of the said parts as are located at that side, are shown in the drawings. The said parts, however, and the means for operating them form no part of the present invention, and 85 for that reason no further description thereof is considered necessary.

The before-mentioned adjustment of the main delivery tapes 6, whereby their upper flights may be located either between and 90 above the reciprocating carriage tapes 7 for co-operation therewith, or between and above the fly sticks 8 when the fly delivery is operating, is effected by raising and lowering the tape pulley shaft 9 at the delivery 95 board end of the mechanism. For this purpose the said tape pulley shaft 9 is supported at each end in the upper end of an upstanding arm 10 secured to a so-called connecting shaft 11 extending transversely 100 across the machine beneath and parallel with the shaft 9.

The connecting shaft 11 is freely supported in a pair of arms 12 secured to a rock shaft 13 which is journalled in the two side 105 frames 14 of the machine and has fast or detachably secured on one end, a hand lever 15 by which it can be rocked for effecting the

raising and lowering of the tape pulley shaft 9. The upstanding arms 10 are held in their different positions of adjustment by a clamping bolt 16 passing through the respective side frame 14 and through a slot 17 in a downwardly extending lock arm 18. This arm is loose on the shaft 11 but can be rigidly attached thereto through another arm 19 which itself is fast on said shaft and to which it can be clamped by a bolt 20 penetrating both of the arms 18, 19. The arm 19 receives the bolt 20 in a slot 21 which enables the upstanding arms 10 to be adjusted angularly to compensate for any variations arising from the stretching or shrinking of the delivery tapes 6, the bolt 20 being released before, and tightened after, such adjustment is made.

The before mentioned slot 17 is arcuate or otherwise shaped so that when the hand lever 15 is operated, the tape pulley shaft 9 is constrained to move arcuately about the axis of the tape pulley shaft 22 adjacent to the impression cylinder 23, whereby the delivery tapes 6 are maintained at the same tension throughout such operation. The tape pulley shaft 9, however, is so far distant from the shaft 22 and its total extent of adjustment is so small, that the constraint imposed by the slot 17 may be such that the adjustment of the shaft 9 is in a vertical plane.

For enabling the sheets to pass from the main delivery tapes 6 on to the fly sticks 8 during the printed side down delivery, means are provided whereby the ends of the sticks adjacent to the impression cylinder 23 can be lowered so that they shall alight in a plane beneath that containing portions of the tapes adjacent thereto. This result may be obtained by so constructing the rack 50 that it can be adjusted relatively to the mechanism operating it, i. e. in the direction of its length by which means the toothed segments 51 can be turned anti-clockwise about the axis of the fly shaft 25 and correspondingly lower the fly sticks to the desired extent. When the fly sticks are operating for the printed side down delivery the reciprocating carriage is in known manner disconnected from its operating mechanism and remains at rest in a position clear of the delivery board.

During the printed side up delivery by the main delivery tapes 6, the sheets pass closely beneath the fly sticks 8 which thus serve as sheet guard sticks to prevent the leading edges of the sheet from curling; to ensure that those edges shall be similarly controlled after they leave the fly sticks, bent guide fingers 24 are secured to the fly shaft 25 so as to ensure the sheets correctly reaching the sheet stop fingers 26. While in the condition of working last described, the rack 50 is in the well-known manner dis-

connected from its operating cam so that the fly sticks remain at rest. The guide fingers 24 and the sheet stop fingers 26, are required only during the printed side up delivery operation of the apparatus, and for that reason both of these devices are readily removable for enabling the conversion from that delivery to the printed side down delivery. To that end the guide fingers 24, as shown in dotted lines in Figure 2, are each secured to a shoe or clamp 27 which can be rigidly attached to, and readily detached from, the fly shaft 25 as by a bolt or screw 28, and the rod 29 carrying the sheet stop fingers 26, is, as is already well known in the art, held in operative position by means of couplings which, when detached, as can easily be done, permit the said rod 29 together with the fingers 26 thereon being removed from the machine as a single entity.

The present invention further involves provision whereby the sheet guard fingers 30 at the receiving end of the main delivery tapes 6, the fly stick rest rod 31, and the delivery board 32 can be adjusted to accord with the changes from one to the other type of delivery. For example, the rod 33 on which are carried the sheet guard fingers 30, may be adjustably mounted in stationary slotted arms 34 so that they can be moved into interlapping relationship with the free ends of the fly sticks 8 as indicated in Figure 1, to co-operate with those sticks in guiding the sheets during printed side up delivery, and out of such relationship as when the said sticks are operated for delivering the sheets printed side down.

The fly stick rest rod 31 is mounted in two forked arms 35 pivoted upon stationary coaxial pivots 36, so that they may be moved into a position to enable the rod to fulfill its normal function as a rest rod for the fly sticks during the intervals at which the latter are receiving the sheets preparatory to swinging them printed side down on to the delivery board 32. During printed side up delivery, the rod 31 may be removed and the arms 35 moved into the lower position. The extent of adjustment of the arms 35 is determined by stationary stops 37 with which a block 37^a operatively fast to said arms 35 engages. The rod 31 is secured to the arms with a capacity for ready detachment so that it can be disconnected from the arms prior to their being moved from the upper to the lower of their terminal positions, and re-instated therein if desired, after the completion of this movement.

The before-mentioned adjustment of the delivery board 32, is provided for by supporting said board, at its inner end, alternatively in one or other of two pairs of hooks or sockets 38 which receive a rod or studs 39 rigidly attached to the delivery board, and at its outer end by pins 40 adjustably

secured in brackets 41 fast to the delivery board, and bearing on brackets 42 fast to the rails 3, the delivery board being clamped to the pins 40 at any desired height by any convenient means such as the clamping screws 40.

43 is the before mentioned sprocket chain which controls the operation of the delivery carriage tapes 7; 44 is the chain stop which 10 engages with the chain 43; 45 is the rock shaft which carries the stop 44; 46 is a toggle arm fast on the shaft 45, which co-operates with a second toggle arm 47 to retain, under the influence of a spring 48, the chain stop 44 in its terminal position until it is positively moved therefrom; 49 are two adjustable stops for limiting the motion of the toggle arm 46 and chain stop 44, and 50 is the rack and 51 the segment meshing there-with for swinging the fly sticks 8; all of these elements are of ordinary construction and constitute no part of the present invention.

Having described our invention, we declare that what we claim and desire to secure by Letters Patent is:—

1. In sheet delivery mechanism for printing machines, the combination of a set of main delivery tapes, a reciprocating delivery carriage having endless carriage tapes reciprocating therewith adapted to receive sheets from the main delivery tapes and deposit them printed side up on the delivery board, and a set of fly sticks adapted to receive sheets from the main delivery tapes and deposit them printed side down directly on the delivery board when the reciprocating delivery carriage is inoperative.

2. Sheet delivery mechanism according to claim 1, characterized by means adapted to adjust the main delivery tapes so that their upper flights shall travel either above the fly sticks or in a plane between the said fly sticks and the plane in which travel the upper flights of the carriage tapes.

3. In sheet delivery mechanism for printing machines, the combination of a set of main delivery tapes, a reciprocating delivery carriage having endless carriage tapes reciprocating therewith adapted to receive sheets from the main delivery tapes and deposit them printed side up on the delivery board, a set of fly sticks adapted to receive sheets from the main delivery tapes and deposit them printed side down directly on the delivery board when the reciprocating delivery carriage is inoperative, and means adapted to adjust the main delivery tapes so that their upper flights shall travel in a plane between the fly sticks and the plane in which travel the upper flights of the carriage tapes when the fly sticks will serve as guards to prevent curling or displacement of the sheets while on said main delivery tapes, or above the fly sticks.

4. In sheet delivery mechanism for printing machines, the combination with devices according to claim 1 of a fly stick rest rod, and means adapted to support said rod with a capacity for removal from below the fly sticks when the printed side up delivery is in operation.

5. In sheet delivery mechanism for printing machines, the combination of a set of main delivery tapes, a reciprocating delivery carriage having carriage tapes reciprocating bodily therewith adapted to receive sheets from the main delivery tapes and deposit them printed side up on the delivery board, a set of fly sticks adapted to receive sheets from the main delivery tapes and deposit them printed side down on the delivery board, means adapted to adjust the main delivery tapes so that their upper flights shall travel in a plane between the fly sticks and the plane in which travel the upper flights of the carriage tapes when the fly sticks will serve as guards to prevent curling or wholly displacement of the sheets while on said main delivery tapes, or above the fly sticks, and means adapted to support the delivery board with a capacity for vertical adjustment corresponding with changes in the height of the main delivery tapes.

6. In sheet delivery mechanism for printing machines, the combination of a set of main delivery tapes, a reciprocating delivery carriage having carriage tapes reciprocating bodily therewith adapted to receive sheets from the main delivery tapes and deposit them printed side up on the delivery board, a set of fly sticks adapted to receive sheets from the main delivery tapes and deposit them printed side down on the delivery board, and sheet guide fingers and means detachably securing said fingers to the fly shaft.

7. In sheet delivery mechanism for printing machines, the combination with a set of main delivery tapes, two sets of pulleys about which these tapes travel, one set at the delivery board end and the other set at the receiving portions of said tapes, a reciprocating carriage, and a set of endless tapes reciprocated bodily with the carriage and adapted to receive the sheets from the main delivery tapes and deposit them printed side up on the delivery board, of means adapted to raise and lower the set of main delivery tape pulleys located at the delivery end of said tapes.

8. In sheet delivery mechanism for printing machines, the combination with a set of main delivery tapes, two sets of pulleys about which these tapes travel, one set at the delivery board end and the other set at the receiving portions of said tapes, a reciprocating carriage, and a set of endless tapes reciprocated bodily with the carriage and adapted to receive the sheets from the main

delivery tapes and deposit them printed side up on the delivery board, of means adapted to raise and lower the set of main delivery tape pulleys located at the delivery end of 5 said tapes and means constraining these movements to a circular arc concentric with the set of main delivery tape pulleys at the receiving portions of said tapes.

9. In sheet delivery mechanism for printing machines, the combination with a set of main delivery tapes, a reciprocating delivery carriage having endless carriage tapes reciprocating therewith adapted to receive sheets from the main delivery tapes and deposit them printed side up on the delivery board, a set of fly sticks adapted to receive sheets from the main delivery tapes and deposit them printed side down directly on the delivery board when the reciprocating delivery carriage is inoperative, a set of pulleys about which the main delivery tapes travel at their receiving portions, and a second set of pulleys at the delivery board end of the main delivery tapes, of a tape pulley shaft carrying this second set of pulleys, arms supporting this tape pulley shaft, a connecting shaft parallel with that last mentioned, to which the arms are secured and means adapted to raise and lower the connecting shaft, of a lock arm loose on the connecting shaft, means adapted to secure said lock arm in different positions of adjustment of the connecting shaft, an arm fast to the connecting shaft adjacent the lock arm, screw-and-slot connections adapted to secure the two last-named arms in different angular positions.

10. In sheet delivery mechanism for printing machines, the combination with a set of main delivery tapes, a reciprocating delivery carriage having endless carriage tapes reciprocating therewith adapted to receive

sheets from the main delivery tapes and deposit them printed side up on the delivery board, a set of fly sticks adapted to receive 45 sheets from the main delivery tapes and deposit them printed side down directly on the delivery board when the reciprocating delivery carriage is inoperative, a set of pulleys about which the main delivery tapes travel at their receiving portions, and a second set of pulleys at the delivery board end of the main delivery tapes, of a tape pulley shaft carrying this second set of pulleys, arms supporting this tape pulley shaft, a 50 connecting shaft parallel with that last mentioned, to which the arms are secured and means adapted to raise and lower the connecting shaft, of a lock arm loose on the connecting shaft, means adapted to secure said lock arm in different positions of adjustment 55 of the connecting shaft, an arm fast to the connecting shaft adjacent the lock arm, screw-and-slot connections adapted to secure the two last-named arms in different 60 angular positions relatively to the connecting shaft, and means constraining the raising and lowering movements of the tape pulley shaft to a circular arc concentric with the set of main delivery tape pulleys at the 65 receiving portions of said tapes.

11. Sheet delivery mechanism according to claim 1, characterized by means adapted to adjust the main delivery tapes from a position in which their upper flights are in a plane below that occupied by the upper flights of the carriage tapes to a position in which this relationship of said upper flights is reversed.

In testimony whereof we have affixed our 80 signatures hereto.

THOMAS ROBERT GILLETT PARKER.
FRED SPENCE.
